UNITED STATES PATENT OFFICE.

ABRAHAM SIMONS, OF SCHENECTADY, NEW YORK.

FLUSH-METER.

No. 913,776.

Specification of Letters Patent.

Patented March 2, 1909.

Application filed June 29, 1908. Serial No. 440,862.

To all whom it may concern:

Be it known that I, ABRAHAM SIMONS, a subject of the Czar of Russia, residing at Schenectady, county of Schenectady, and State of New York, have invented certain new and useful Improvements in Flush-Meters, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

This invention is especially adapted for use in flushing closet-bowls.

The principal objects of the invention are to provide means for flushing the bowl during a predetermined interval of time and for regulating the duration of such interval as may be desired.

The invention consists of a case-valve having ingress and egress openings, a main passageway and a pressure-regulating passageway connecting such openings, a differential valve movable along a part of the regulating passageway but controlling the main passageway, a valve for controlling the regulating passageway, means for operating the pressure-regulating valve, whereby the actuating pressure upon the differential valve is controlled, and means for limiting the extent of movement of the differential valve, whereby the duration of the flushing operation can be varied as desired.

Figure 1 is a view in side elevation of the improved meter. Fig. 2 is a vertical longitudinal central section of the same showing the flushing valve closed. Fig. 3 is a similar section showing the valve opened. Fig. 4 is a top plan view of the meter as shown in Fig. 1. Fig. 5 is a top plan view of the valve-stop detached. Fig. 6 is an edge view of the same. Fig. 7 is a bottom plan view of the differential valve detached. Fig. 8 is a side elevation of the same. Fig. 9 is a top plan view of the valve-seat block detached. Fig. 10 is a side elevation of the same.

The meter comprises a containing case, 1, having an ingress opening, 2, and an egress opening, 3, which openings are separated

by the diaphragm 4 preferably cast integral with the case. A valve seat-block, 6, shown detached in Figs. 9 and 10, is inserted in an aperture in the diaphragm adapted to receive and closely fit the same, as seen in Figs. 2 and 3. The seat-block is provided with oppositely-disposed annular grooves, 7, one on its upper side and one on its lower side, which grooves are connected by a series of apertures, 8, extending through the seat-block and forming parts of the main passageway connecting the ingress and egress openings. This seat-block is also provided with the central aperture 10, in which is fixed the lower end of a tubular post, 12, which forms a slide-way or guide for the differential valve, 14. This valve consists of the lower member, 15, adapted to close the apertures 8 in the seat-block and the member 16, having a greater cross-sectional area than the member 15, and adapted to approximately close and move along the run-way, 17. The two members 15 and 16 are connected by the tubular body-portion, 18, which is adapted to receive and loosely fit upon the post 12. The tubular post extends upwardly along the center of the run-way 17, and beyond the same, into chamber 20, formed in the cap 21, which cap is detachably secured to the upper end of that part of the case-wall which contains the run-way, by means of screw-threads, 22, on the cap and case-wall. The upper end of the tubular post is screw-threaded exteriorly to receive the valve-stop, 24, containing a central screw-threaded aperture, 25, adapted to receive and fit the post. The convex peripheral edges, 26, are concentric and adapted to fit the interior of that part of the case containing the run-way, and are capable of being moved longitudinally of the run-way when the stop is rotated on the post, thereby varying the length of the run-way. The indentations, 28, form openings which connect the run-way with the cap-chamber. The upper end of the tubular post is provided with a conical valve, 30, provided with a stem, 31, passing down through and projecting from the lower end of the tubular post.

When this valve is opened, a regulating passageway is formed leading from the ingress opening 2 up the run-way 17, through openings 28, into the cap-chamber 20, down the passageway in the tubular post to the egress opening 3.

As a means for operating the regulating

valve 30, there is provided a rock-shaft, 32, rotatory in bearing 34, having on its outer end an operating handle, 35, and on its inner end a sleeve, 36, fixed on the shaft and 5 provided with rock-lever, 37, adapted to engage the lower end of the stem 31; also the stops 38 and 39, adapted to engage a case-lug, 40, for the purpose of limiting the rock-movements of the shaft. The valve is shown 10 closed in Fig. 2, and opened in Fig. 3. It is not essential that the regulating passageway should lead to the egress opening 3. In Fig. 2 the main or differential valve and the regulating valve are both shown in closed position. The ingress opening 2 being connected with a water-supply pipe, the hydrostatic pressure of the water maintains both valves in closed position. The upper member 16 of the main valve being somewhat smaller in 15 cross-sectional area than the cross-sectional area of the run-way 17, leaves an open passageway of comparatively small capacity between the ingress opening, run-way 17 and the cap-chamber 20 so that the full hydrostatic pressure of the water acts upon the 20 regulating valve to maintain the same in a closed position, and also upon the lower member 15 of the main valve to close the latter valve, the pressure upon the upper side 25 of the member 16 being sufficient to balance the pressure upon the lower side of such member.

The flushing operation of the device is as follows: The crank-handle 35 is lifted by 35 the hand of the operator, which positively opens the regulating valve 30, thereby opening the regulating passageway and relieving the hydrostatic pressure upon the upper side of the upper member 16 of the main valve, 40 which causes the pressure upon the lower side of such member to open the main valve and raise it from the position shown in Fig. 2 to that shown in Fig. 3, the water which was in the run-way 17 above the main valve 45 passing freely through the apertures 28 down the tubular post to the atmosphere, or the egress opening 3. The operating crank-handle is then released, which allows the regulating valve to close by gravity. Immediately upon the closing of such valve, the 50 hydrostatic pressure upon the main valve becomes balanced, whereupon the main valve slides by gravity down the tubular post and along the run-way 17 to the position which 55 closes the main passageway, shown in Fig. 2. The speed at which the differential or main valve descends along the run-way depends upon the area of the opening between such 60 valve and the case-wall containing the run-way, because the water in the run-way beneath the valve, when at its highest position, as shown in Fig. 3, must pass the valve while

the latter is descending. The time required for the valve to descend to its closing position also varies directly as the length of the 65 run-way. By lengthening the run-way, the time of descending is increased, and the time required for the valve to descend is shortened by shortening the run-way. It is obvious that the main passageway continues 70 open while the differential valve is descending. The adjustable stop 24 affords a means for lengthening and shortening the run-way, and thereby regulating the time-length of the flushing-period. By removing the cap 75 21, the adjustable stop is rendered easily accessible for changing its adjustment.

What I claim as new and desire to secure by Letters Patent is—

In a flush-meter of the class described, the 80 combination with a case having ingress and egress openings, main and regulating passageways, and a vertical run-way forming a part of the regulating passageway; of a diaphragm between such openings, containing 85 apertures which form a part of the main passageway; a tubular guide-post erected from such diaphragm, extending down through such diaphragm and upwardly 90 along the central line of such run-way and beyond the same; a differential valve comprising a tubular body adapted to receive and slide upon the tubular post, having at its lower end a member adapted to close the apertures in the diaphragm, and upon its 95 upper end a member larger in cross-sectional area than the member at the lower end and adapted to approximately close and move along the run-way to its upper end; a stop at the upper end of the run-way for limiting the upward movement of the differential valve and adjustable longitudinally of the tubular guide-post, whereby the length of the run-way may be varied by changing the 100 adjustment of the stop; a detachable cap secured to the upper end of the case-wall containing the run-way, having a closed chamber containing the upper end of the post and connecting with the run-way; a gravity-closing valve for closing the regulating 105 passageway which leads from the inlet opening up the run-way into the cap-chamber and down the tubular post; a valve-controlling stem extending from the regulating valve down through the tubular post, and means 110 extending exteriorly of the case for raising 115 such stem to open such valve.

In testimony whereof, I have hereunto set my hand this 26 day of June, 1908.

ABRAHAM SIMONS.
